UNITED STATES PATENT OFFICE

144,978

DESIGN FOR A FONT OF SIGN PANEL LETTERS

Harold R. Owen, Venice, Calif., assignor to Electrical Products Corporation, Los Angeles, Calif., a corporation of California

Application May 5, 1945, Serial No. 119,415

Term of patent 14 years

(Cl. D64—12)

To all whom it may concern:

Be it known that I, Harold R. Owen, a citizen of the United States, residing at Venice, in the county of Los Angeles and State of California, have invented a new, original, and ornamental Design for Font of Sign Panel Letters, of which the following is a specification, reference being had to the accompanying drawing, forming part thereof.

Fig. 1 is a plan view of a font of sign panel letters showing my new design; and

Fig. 2 is a fragmentary perspective view partially in section on an enlarged scale for the purpose of bringing out more clearly the details of ornamentation, the portion selected representing, for example, the letter U, which is characteristic of each letter having a bottom loop.

As illustrated in the drawing, all letters both

of the straight bar and of the looped type have rounded corners, and the general disposition of the letters upon their respective panels is such that an appearance of substantially uniform spacing is produced at the sides of the letters and also between adjacent letters forming words in a sign structure. The panels generally have the same width, and also the same height, in a given alphabet. The background of each panel is in the form of columns of substantially uniform width yielding fluted effects, the strokes forming the bodies of the individual letters being smooth faced, and the width of the panels being in multiples of the width of the columns.

I claim:

The ornamental design for a font of sign panel letters, as shown and described.

HAROLD R. OWEN.
